UNITED STATES PATENT OFFICE.

WILLIAM A. SEIDEMANN AND JOSEPH JOHNSON, OF MILWAUKEE, WISCONSIN, AS
SIGNORS TO SNAP-ON WRENCH COMPANY, OF MILWAUKEE, WISCONSIN, A COR-
PORATION OF WISCONSIN.

TAP WRENCH.

Application filed June 7, 1922. Serial No. 566,541.

To all whom it may concern:

Be it known that we, WILLIAM A. SEIDEMANN and JOSEPH JOHNSON, citizens of the United States, and residents of Milwaukee, in the county of Milwaukee and State of Wisconsin, have invented new and useful Improvements in Tap Wrenches, of which the following is a description, reference being had to the accompanying drawings, which are a part of this specification.

10 The invention relates to tap wrenches.

The general object of the invention is to provide an adjustable tap wrench attachment for wrench sets having interchangeable handles and sockets, the handles being of various shapes and lengths but having a detachable interfitting driving connection with the attachment.

15 A further object of the invention is to produce an inexpensive, compact and simple tap wrench attachment for wrench sets.

With the above and other objects in view the invention consists in the construction hereinafter described and claimed and all 20 equivalents.

25 In the drawings: Fig. 1 is a vertical sectional view through a device embodying the invention; Fig. 2 is an end view of the attachment, parts being broken away; Fig. 3 is a side view of the attachment; Fig. 4 is a detail view of one of the jaws.

30 An operating handle 5, which may be interchangeable with one or more others having different shapes, is provided with a squared or polygonal end 6 having stops 7 punched therefrom and a friction catch of well known construction comprising a ball 8 mounted in a transversely extending opening 9 and limited in its movement by 35 a retaining crimped portion 10, and a spring 11 serving to move the ball to a position to engage the socket of the member in which the shank of the handle is inserted.

35 A member 12 has a squared or polygonal socket 13 formed therein to detachably receive the polygonal shanks of interchangeable handles 5 or other parts of the wrench set that may be used with the tap wrench. This member 12 is provided with a transversely extending bore 14 and a transversely 40 extending slot 15 which extends down to a position intersecting the upper part of

the bore 14 and forms shoulders 16 adjacent said bore.

45 A right and left hand jaw-moving-and-clamping screw 17 is mounted in the bore 14 and as the slot 15 terminates short of the horizontal axis of the bore 14 the screw 17 will be journaled in said bore and it is prevented from moving laterally in said bore by a pin 18. This pin 18 is disposed in a hole 19 extending vertically from the bottom of the socket 13 down into the bore 14 and its lower end projects into a centrally disposed annular groove 20 in the 50 screw. The head end of the pin 18 is firmly held to the member 12 as by upsetting it.

55 Blocks 21, forming jaw members, are slidably mounted in the slot 15 and provided with partial threads 22 engageable with the screw 17 and with V-notched tap-engaging faces 23. These blocks are held in their proper position relative to the screw and with parts 24 of the threaded 60 faces disposed against the shoulder 16 by a ring-shaped retainer plate 25 secured to the member 12 by screws 26. The screw 17 is provided with a square socket 27 to detachably receive the squared end of the 65 usual handle member 28 whereby to turn said screw so as to tightly clamp the shank of a tap 29 between the jaws 21, the spread of the jaws permitting the attachment to be used with a number of taps of different 70 sizes.

75 What we claim as our invention is:

1. A tap wrench attachment for wrench sets comprising a member having a socket in one end to detachably interfit with an 80 operating handle and having a transversely disposed bore and a slot extending from the other end of said member into the bore and terminating at a distance short of the horizontal axis of the bore to form guide shoulders adjacent the bore, a rotatable jaw-clamping screw journaled in said bore and having a centrally disposed annular groove, said member having a vertically disposed 85 hole extending from the bottom of the socket to said transverse bore, a pin disposed in said vertically disposed hole and having its end extending into said groove to prevent lateral movement of said screw, tap- 90 95 100

clamping jaws slidably mounted in said slot and having threaded portions engaged by the screw, and a plate secured to the slotted end of said member and forming a retainer for said jaws and provided with a central opening adjacent the clamping faces of the jaws.

2. A tap wrench attachment comprising a member having detachable connection with an operating handle and having a transversely disposed bore and a slot extending from the bottom end of said member into the lower part of the bore with the inner end of the slot forming guide shoulders adjacent the bore, a rotatable jaw-clamping screw journaled in said bore, means for preventing lateral movement of said screw with respect to said member, tap-clamping jaws slidably mounted in said slot and having threaded portions engaged by said screw, and a plate secured to the bottom end of said member and forming a retainer

for said jaws and provided with a central opening adjacent the clamping faces of the jaws.

3. In a tap wrench attachment for wrench sets, the combination of a member having a socket in one end to detachably interfit with an operating handle, a rotatable jaw-clamping screw mounted within said member and having a centrally disposed annular groove, said member having a vertically disposed hole extending from the bottom of the socket, a pin disposed in said vertically disposed hole and having its end extending into said groove to prevent lateral movement of said screw, and tap-clamping jaws mounted within said member and operatively connected to said screw.

In testimony whereof, we affix our signatures.

WILLIAM A. SEIDEMANN.
JOSEPH JOHNSON.
